UNITED STATES PATENT OFFICE.

DENNIS HASTINGS AND ANDREW W. BRINK, OF NEW MARTINSVILLE, WEST VIRGINIA.

GAS-COOLING AND GASOLENE-SEPARATING APPARATUS.

No. 867,505.

Specification of Letters Patent.

Patented Oct. 1, 1907.

Application filed December 10, 1906. Serial No. 347,148.

To all whom it may concern:

Be it known that we, DENNIS HASTINGS and ANDREW W. BRINK, citizens of the United States, residing at New Martinsville, in the county of Wetzel and 5 State of West Virginia; have invented a new and useful Gas-Cooling and Gasoline-Separating Apparatus, of which the following is a specification.

This invention relates to apparatus for cooling compressed gas and separating gasoline and other light 10 liquid hydro-carbons from natural gas at the compressing station or at the well.

One of the principal objects of the invention is to provide means of simple and comparatively inexpensive construction in which the gas under natural pressure 15 sure from the well, or after being artificially compressed, is brought into contact with water which serves to cool the gas, and at the same time to separate the light liquid hydro-carbons therefrom, as well as to wash and purify the gas in order to prevent deposits in 20 the gas mains, and at the burner tips.

A further object of the invention is to provide an apparatus of this character in which a stream of gas under pressure is brought into contact with a spray of water or other liquid, and then is allowed to slightly 25 expand, in order to reduce the velocity, and to permit the more ready separation of the light liquid hydro-carbon and impurities.

With these and other objects in view, as will more fully hereinafter appear, the invention consists in certain 30 novel features of construction and arrangement of parts, hereinafter fully described, illustrated in the accompanying drawings, and particularly pointed out in the appended claims, it being understood that various changes in the form, proportions, size and minor 35 details of the structure may be made without departing from the spirit or sacrificing any of the advantages of the invention.

In the accompanying drawings:—Figure 1 is a plan view, partly in the nature of a diagram, of an apparatus 40 for cooling compressed gas and separating gasoline therefrom, constructed in accordance with the invention. Fig. 2 is an elevation, showing a slight modification of the invention for use at a natural gas well, or to be connected in one of the pipe-lines leading therefrom. Figs. 3 and 4 are detail sectional views on the lines 3—3 and 4—4, respectively of Fig. 1.

Similar numerals of reference are employed to indicate corresponding parts throughout the several figures of the drawings.

The apparatus shown in Fig. 1 is located in a stream 50 of running water or in a reservoir of water, as indicated at 10. The gas under compression enters through a header 15, and passes through a plurality of pipes 16 to

an intermediate header 17, from which the gas flows at slightly reduced temperature through a series of 55 pipes 18 which lead to separating pipes 19 of greater diameter than the pipes 18, and thence flows from the pipes 19 through smaller pipes 20 to a header 21, from which the gas is carried to a holder, or to the point where it is to be used. Near the discharging end of each of 60 the pipes 18 is arranged a liquid spray tube 22, through which water or oil is forced under pressure from a suitable pump 23, the liquid being atomized, so as to more thoroughly intermingling with the stream of gas. The atomized liquid is preferably at a low temperature and 65 reduces the temperature of the gas to a considerable extent, it being understood that the gas under natural or artificial pressure is highly heated.

The mingled gas and water or oil passes into the separating pipes 19, which, being of larger diameter than 70 the pipes 18, permits expansion of the gas and slightly checks the speed at which the streams of gas are moving, so that there is ample opportunity for the separation of the gasoline and other light hydro-carbons, and 75 impurities from the gas proper. All of the liquid will flow by gravity to the lower portions of the pipes 19, while the gas is free to pass off through the pipe 20 to the discharge header 21. The liquid flows from the discharge end of each pipe 19 through a small pipe 25 to a receiving pipe 26, from which it flows by gravity, 80 or is pumped to a collecting tank 30, the liquid passing through an automatic trap or traps 31 in order to prevent the passage of the gas into the receiving tank. If water is used, the gasoline separates therefrom by 85 gravity and can be readily drawn off into a storage tank. If oil is used, or fluids other than water, such fluid, when gathered into the collecting tank, with the gasoline, can be used over and over by connecting the lower portion of the tank to the suction side of the force pump 23. 90

It is found in practice that where the gas is heated by high compression and cooled in the manner described, the sudden change in the temperature of the gas precipitates a quantity of gasoline therefrom, and this is found to be a very economical and profitable method of 95 gathering gasoline without interfering with the flow, or reducing the candle power of the gas. A further advantage gained is that by reducing the temperature of the gas, the friction in the pipe line is considerably reduced, and as the impurities are separated from the gas 100 during the washing process, there is less deposit in the pipe lines.

Where the invention is used in connection with natural gas, either at the well or at any point in a pipe-line leading therefrom, the structure is modified as shown in 105 Fig. 2. In this case the pipe 35 through which the

stream of gas flows from the well, is connected to two branch pipes 36, and thence flows through smaller pipes 37 into a liquid reservoir 38 which in the present instance is shown in the form of an elongated tube. The 5 inner portions of the pipes 37 are provided with numerous perforations through which the gas flows in minute streams, and the pipes are submerged in the liquid in said reservoir 38, so that the gas is compelled to pass through the liquid, and in so doing will be 10 cooled, and at the same time will permit the separation therefrom of the gasoline and other light hydro-carbons, after which the gas passes off through pipes 39 to a discharge pipe 40. The gasoline separates from the liquid in the reservoir 38 by gravity, rising to the top of such liquid, and flowing off through pipes 41 to a recycling pipe 42, and thence passing to a storage or collecting tank 43.

By using this device, the gasoline is separated from the natural gas at very slight expense, without stop-

ping the flow of the gas, and without decrease in the 20 candle power thereof.

We claim:

In apparatus for removing gasoline from gas under compression, a reservoir constructed to contain a cooling fluid, a plurality of headers arranged in the reservoir, cooling 25 pipes connecting the headers, expansion chambers connected in the pipes and of greater diameter than said pipes, means for discharging the liquid condensed in said chambers, and water spraying tubes arranged centrally of the pipes and provided with perforations for directing jets of 30 water transversely across the pipes in the path of the streams of gas.

In testimony that we claim the foregoing as our own, we have hereto affixed our signatures in the presence of two witnesses:

DENNIS HASTINGS.
ANDREW W. BRINK.
